UNITED STATES PATENT OFFICE.

AMOS CALLESON, OF BROOKLYN, NEW YORK, ASSIGNOR TO BENJAMIN ADRIANCE, OF BROOKLYN, NEW YORK.

BOTTLE-SUPPORT FOR BOTTLE-SEALING MACHINES.

1,142,078.

Specification of Letters Patent.

Patented June 8, 1915.

Application filed October 15, 1913. Serial No. 795,212.

To all whom it may concern:

Be it known that I, AMOS CALLESON, a citizen of the United States, residing at Brooklyn, in the county of Kings and State 5 of New York, have invented certain new and useful Improvements in Bottle-Supports for Bottle-Sealing Machines, of which the following is a specification.

In view of the circumstance that bottles 10 frequently have their bases or bottoms formed so that the supporting plane thereof is not perpendicular to the vertical axis of the bottle, it becomes necessary in the operation of sealing bottles by machines of the 15 class in which pressure is exerted longitudinally of the bottles to effect sealing to provide a seat that will yield in such manner as to compensate for the irregularity referred to. The kind of seat heretofore 20 used was a rubber or similar form of pad. Seats of this kind, as is well known, soon become incapacitated by reason of the wear incident to the constant application of pressure, making it necessary frequently to 25 replace them with fresh ones.

My object is to provide a seat that may be 30 made of imperishable material, such as metal or any other hard, durable substance, and at the same time will be capable of adjusting itself to irregularities of bottle-bases 35 or bottoms with the same efficiency as seats formed of rubber or the like.

To this end, my invention consists in providing a machine of the kind indicated with 40 a seat capable of tilting (in the preferred form, by a rolling action) and in that way affording compensation for irregularities in the bottoms or bases of the bottles or other containers supported thereon.

Referring to the accompanying drawings, 45 Figure 1 shows a bottle being subjected to sealing pressure in a bottle sealing machine having the means for supporting the bottle constructed in accordance with this invention, only the said means and the sealing head of the machine being shown and they appearing in section; Fig. 2 is a plan of the aforesaid means; and, Fig. 3 shows the means aforesaid, the bottle seat and the support therefor appearing in section on the line $x-x$ in Fig. 2.

In a suitable support a , which may be the

rotary turret or the like of a bottle sealing machine of the type in which the bottles are carried in the arc of a circle under the sealing head, is arranged a circular series of upwardly open recesses b . In the preferred form each recess has a flat bottom surface c and its side wall d is conical, the lesser diameter of the recess being at the top—that is, 55 in the plane of the top surface of the support a .

In each recess is arranged a disk e of metal or other hard substance whose top surface is preferably flush with the top surface of the 60 support a , so as to permit the container to be shifted from one to the other of said surfaces. The underneath surface f of this disk, which constitutes the seat aforesaid, is convex, the greatest thickness of the disk 65 being at the center thereof, so that the disk is capable of tilting universally; preferably, the said surface f is universally rounded, so that when the disk tilts it does so with a 70 rolling action.

Assuming, now, that a bottle A having the supporting plane of its bottom or base B out of perpendicular to the vertical axis of the bottle (and it will be understood that it may be either perfectly flat or formed with 80 a protuberance or protuberances and yet have its supporting plane out of perpendicular to such axis) and that such bottle is placed upon the seat e in position to be subjected to sealing pressure effected by the 85 coöperation of the sealing head g shown in Fig. 1 and the seat carrying support a , when such pressure is exerted the seat e will roll on the surface c until it has become tilted to such a position as compensates for the 90 supporting plane of the bottom or base of the bottle being out of the perpendicular to the bottle's vertical axis, as shown in Fig. 1, where the irregularity of the bottle appears somewhat exaggerated so that the tilting of 95 the seat e will be clearly apparent. After the removal of the bottle the seat will of course reassume the position shown in Fig. 3, where its top surface is perfectly flush with the top surface of the support a .

In practice I preferably place a sealing ring of rubber or the like h between the periphery of the seat e and the wall d of the recess, the same being designed to prevent par-

ticles of glass and grit from having access into the recess and so interfering with the tilting action of the seat.

Having thus fully described my invention, what I claim as new and desire to secure by Letters Patent is:—

- 5 1. In a machine for exerting pressure on a container in the direction of a line extending through its base or bottom, the combination of a recessed supporting member and a tilting seat member arranged in the recess of and supported by the supporting member, said members having approximately flush container supporting surfaces.
- 10 2. In a machine for exerting pressure on a container in the direction of a line extending through its base or bottom, the combination of a recessed supporting member, a tilting seat member arranged in the recess

of and supported by the supporting member, 20 and elastic means opposing yielding resistance to tilting movement of the seat member.

- 25 3. In a machine for exerting pressure on a container in the direction of a line extending through its base or bottom, the combination of a suitable recessed support, a tilting seat member receiving the contact of the container and arranged in the recess of said support, and sealing means surrounding said seat and fitted between the same and the 30 surrounding surface of said recess.

In testimony whereof I affix my signature in presence of two witnesses.

AMOS CALLESON.
